CLAIM

The ornamental design for a squeegee tool, as shown and described.

DESCRIPTION

FIG. 1 is a front, top perspective view of my design for a squeegee tool;

FIG. 2 is a front, bottom perspective view thereof;

FIG. 3 is a front view thereof;

FIG. 4 is a rear view thereof;

FIG. 5 is a side view thereof, the opposite side being a mirror image thereof;

FIG. 6 is a top view thereof; and,

FIG. 7 is a bottom view thereof.

The broken lines in the figures depict portions of the squeegee tool that form no part of the claimed design.
